UNITED STATES PATENT OFFICE.

HEZEKIAH FORSYTH, OF DETROIT, MICHIGAN.

FOLDING CHAIR.

SPECIFICATION forming part of Letters Patent No. 451,475, dated May 5, 1891.

Application filed June 12, 1890. Serial No. 355,189. (No model.)

To all whom it may concern:

Be it known that I, HEZEKIAH FORSYTH, a citizen of the United States, residing at Detroit, county of Wayne, State of Michigan, 5 have invented a certain new and useful Improvement in Folding-Chairs; and I declare the following to be a full, clear, and exact description of the same, such as will enable others skilled in the art to which it pertains to make 10 and use the same, reference being had to the accompanying drawings, which form a part of this specification.

It is the object of my invention to produce a folding chair which shall be useful as a 15 lawn-chair, a camp-chair, a camp-cot, an invalid's chair, and the like; and it consists in a combination of devices and appliances hereinafter described and claimed.

In the drawings, Figure 1 is a side elevation of my chair. Fig. 2 is a plan, and Fig. 3 is a view showing the chair suspended.

In carrying out the invention, E represents the main back pieces or uprights, at the top of which is a cross-piece E'. To this cross- 25 piece E' the upper end of the canvas F is engaged.

G are upright pieces at the front of the chair, their upper ends connected together by the cross-round G', and adjacent to the lower end 30 they are connected together by the cross-piece G². The canvas F, being engaged to the cross-piece E', extends down parallel with the back pieces and outward to the upper ends of the uprights G, over the cross-piece G', and down 35 to the cross-piece G², where it is rigidly engaged.

H H are side pieces extending from the upper ends of the pieces G back to the upright back pieces E, where they are pivotally engaged, and J are side pieces extending from 40 the upright G, where they are pivoted back to the lower ends of the upright back pieces E, where they are also pivoted.

K L are diagonal uprights and constitute 45 the supporting-frame of the chair. The uprights L are pivoted at h' to the part H and at m to the part M, while the upright K is pivoted at h to the part H, but has its free upper end resting on L when the chair is 50 open. Now, the parts being pivoted together at j j' j² j³, it will be observed that when a per-

son sits down in the chair and exerts a pressure on the back it will yield, and because of the pivotal engagement of the parts, as shown, the person may assume any position from a 55 horizontal to an upright that may be desired.

In order that the parts may be held in the position desired, I provide the pieces M, pivot them to the upright base portion, as at m, extend them back adjacent to the uprights E, 60 and provide the pin e and notches m', which notches, engaging on the pin, hold the chair in the position desired.

Another important feature of my invention is the provision of a strengthening-frame beneath the seat portion of the canvas—that is, the portion of the canvas where the greatest weight of the person comes when the back of the chair is in an upright position. N are pieces pivoted to the pieces G. They extend 70 back to a point adjacent to or beyond the upright pieces E, and are connected at the back by a suitable cross-piece N'. A piece of canvas is attached to the cross-piece G' and to the cross-piece N' at the rear ends of the 75 pieces N. P is a piece, there being one for each side, pivotally engaged at p to the piece N and provided in the lower end with a slot p', adapted to engage over the pin p² on the piece J. Now, as will be seen, as the upright 80 back portion E assumes a vertical position this re-enforcing frame will be forced up to a point underneath the seating portion of the main canvas and will act to support the canvas at this point and thus prevent the main 85 canvas from sagging down.

If desired, there may be provided a foot piece or frame Q, pivotally engaged to the lower ends of the piece G.

When the chair is suspended, as in Fig. 3, 90 I first fold up the leg or base portion to the position shown, and then pass the suspending-cord from the ends of the pieces K and the pieces H, as shown.

What I claim is—

1. In a folding chair, the combination of 95 the following elements: the pieces E, G, H, and J, pivotally engaged together, as shown, and engaged to a corresponding set of pieces by the cross-pieces G', G², and E', a supporting-frame consisting of the pieces K L, to which the pieces H are pivotally engaged,

and the notched bars M for holding the chair in position, substantially as described.

2. In a folding chair, the combination, with the pieces E, H, G, and J, connected together, substantially as described, and a re-enforcing frame N, supporting a canvas seat and pivoted at its forward end to the pieces G, of the slotted pieces P, pivoted to said frame N

and bearing on pins p^3 on the pieces J, substantially as described.

In testimony whereof I sign this specification in the presence of two witnesses.

10
IEZEKIAH FORSYTH.
